UNITED STATES PATENT OFFICE.

WILLIAM O. STALEY, OF HOUSTON, TEXAS, ASSIGNOR OF FORTY-FIVE ONE-HUNDREDTHS TO HARRY R. DECKER AND TEN ONE-HUNDREDTHS TO F. P. RISDON, BOTH OF HARRIS COUNTY, TEXAS.

PROTECTOR FOR PAPER-ROLLS.

1,267,815.

Specification of Letters Patent. Patented May 28, 1918.

Application filed July 30, 1917. Serial No. 183,418.

To all whom it may concern:

Be it known that I, WILLIAM O. STALEY, a citizen of the United States, residing at Houston, in the county of Harris and State 5 of Texas, have invented certain new and useful Improvements in Protectors for Paper-Rolls, of which the following is a specification.

This invention relates to new and useful 10 improvements in a protector for paper rolls.

The object of the invention is to provide a device of the character described which is specially designed for protecting rolls of paper and preventing the same from becoming 15 mutilated in shipping and in handling.

As is well known, bulk paper, particularly paper used in printing newspapers is formed into rolls for shipping purposes and as at present handled, these rolls are not 20 properly protected and in shipping and handling, the outer plies of the paper often become mutilated and destroyed, causing a great waste. It is the object of this invention to provide a protector which will completely 25 protect the rolls of paper and eliminate this mutilation and waste.

Another object of the invention is to provide a protector which may be cheaply constructed and easily applied to and removed 30 from the paper rolls.

A further feature of the invention resides in the provision of a protector of the character described which is adjustable so as to fit closely around any sized roll of paper.

35 With the above and other objects in view, the invention has particular relation to certain novel features of construction, arrangement of parts and use, an example of which is given in this specification and illustrated 40 in the accompanying drawings wherein:—

Figure 1 shows a side elevation of a paper roll, showing the preferred form of protector applied thereto.

Fig. 2 shows an end view thereof.

45 Fig. 3 shows a side view of a paper roll with another form of protector applied.

Fig. 4 shows a plan view of one of the end plates employed.

Fig. 5 shows a sectional view thereof, and

50 Fig. 6 shows an enlarged fragmentary end view of the protector.

Referring now more particularly to the

drawings wherein like numerals of reference designate similar parts in each of the figures, the numeral 1 refers to a roll of 55 paper. Each end of this roll is protected by the end plates 2, 2, formed of three sections 3, said sections being shown secured together, and forming a circular plate in Fig. 2. Each section has a marginal flange 60 4 standing at right angles thereto, the flanges of the three sections forming a continuous annular rim which completely surrounds the roll of paper at each end. Each flange 4 is formed into a rib 5, the ribs of the adjacent flanges being in alinement and extending entirely around the roll as shown in Figs. 1 and 3 and these ribs are provided with perforations as 6, the corresponding perforations being in alinement to receive 70 the tie rod 7. These rods have heads at one end and their other ends receive the nuts 8 by means of which they are secured in position. Paper for printing purposes is usually rolled on a tubular mandrel as 9 provided to receive the spindle of the printing press and this mandrel is left in the roll until the paper is wound therefrom in the process of printing. The apex of each plate 3 is provided with an oblong slot 10 and 80 when the plates are placed in position, their edges are overlapped as shown in Fig. 2, bringing the slots of the respective plates into alinement and the rod 11 is then inserted through said slots, passing through the 85 tubular mandrel 9. One end of this rod has the head 12 and the other end thereof receives the nut 13 by means of which it is secured in place.

Rolls of paper vary slightly in size and 90 consequently the protector must be made adjustable so that it can be varied accordingly. For that reason, the perforations 6 are made considerably larger in diameter than the tie rod 7 and the oblong slots 10 are provided 95 so as to permit a certain amount of radial movement of the sections 3 relative to each other. When these sections are adjusted to fit closely around the end of the roll, the nuts 8 and 13 may then be screwed up tight 100 so as to clamp and hold said sections closely around, and against the ends of the roll.

In the form shown in Fig. 3, the tie rods 7 are not used but in lieu thereof cords or

wires 14 are employed which are engaged over lugs 16 stuck out from the flanges 4 and by means thereof the end protectors are held firmly against the ends of the roll.

5 In handling and shipping the rolls, the annular ribs 5 hold the paper elevated and prevent it from coming in contact with anything that would likely cause mutilation thereof.

10 What I claim is:

1. A protector for rolls of paper and the like including a cap fitted over each end of the roll, each cap being formed of sections and means securing said sections together, 15 said means also securing said caps on said roll.

2. A protector for rolls of paper and the like including a cap fitted over each end of the roll, each cap being formed of sections 20 adjustable relative to each other, and means securing said sections together, said means also securing said caps on said roll.

3. A device of the character described including end plates adapted to fit against the 25 ends of a paper roll, each plate being formed

of sections and means for securing said plates clamped against the roll ends.

4. A device of the character described including end plates adapted to fit against the ends of a paper roll, each plate being formed 30 of sections adjustable relative to each other, and means for securing said plates clamped against the roll ends.

5. A device of the character described including end plates adapted to fit against the 35 ends of a paper roll, each plate being provided with an annular rib, said ribs supporting the roll spaced from its supporting surface, each plate being formed of sections adjustable relative to each other, and 40 means for securing said plates clamped against the roll ends.

In testimony whereof I have signed my name to this specification in the presence of two subscribing witnesses.

WILLIAM O. STALEY.
